UNITED STATES PATENT OFFICE.

CHARLOTTE DICKIE, OF BLAIRSVILLE, PENNSYLVANIA.

FOLDING BOX AND CRATE.

965,089.

Specification of Letters Patent. Patented July 19, 1910.

Application filed May 5, 1910. Serial No. 559,595.

To all whom it may concern:

Be it known that I, CHARLOTTE DICKIE, a citizen of the United States of America, residing at Blairsville, in the county of Indiana and State of Pennsylvania, have invented certain new and useful Improvements in Folding Boxes and Crates, of which the following is a specification, reference being had therein to the accompanying drawing.

10 This invention relates to folding boxes and crates, and the primary object of my invention is to provide a box or crate that can be advantageously used for shipping various kinds of merchandise, the box being constructed whereby it can be collapsed to occupy a comparatively small space in storage or in a car during return shipment.

15 A further object of my invention is to provide a collapsible box that is simple in construction, durable, rigid in a set-up position, compact in a "knocked-down" position, and highly efficient as an inclosure for various kinds of merchandise.

20 I attain the above objects by a mechanical construction that will be hereinafter specifically described and then claimed, and reference will now be had to the drawing forming a part of this specification, wherein there is illustrated a preferred embodiment of the invention, but it is to be understood that the structural elements thereof can be varied or changed, as to the size, shape, and manner of assemblage, without departing from the scope of the appended claims.

25 In the drawings: Figure 1 is a front elevation of the box or crate in a set-up position. Fig. 2 is a longitudinal sectional view of the same. Fig. 3 is a cross sectional view of the box. Fig. 4 is a similar view 30 showing the box in a folded or "knocked-down" position, and Fig. 5 is a perspective view of a detached locking plate or latch.

35 In the accompanying drawings the reference numeral 1 denotes a bottom plate rectangular in plan and having the edges thereof provided with vertical side plates 2 and 3, the plates 3 being of a greater height than the plates 2.

40 4 denotes end walls hinged to the side plates 2, as at 5, and these walls are adapted to fold inwardly one upon the other.

45 5 and 7 denote rear and front walls hinged, as at 8, to the side plates 3 and these walls are adapted to fold inwardly one upon the other upon the end walls 4. The walls 4,

6, and 7 are provided with central vertical slots 9 and with plates 10 upon the inner and outer sides of the walls, said plates closing the slots and providing pockets for locking plates or latches 11. The lower ends 60 of these locking plates are adapted to extend downwardly into pockets 12 provided therefor in the side plates 2 and 3, said pockets being formed similar to the pockets of the walls 4, 6, and 7, that is, by slotting 65 the plates 2 and 3 and providing inner and outer side plates 13. The upper ends of the locking plates 11 are reduced, as at 14 and provided with recesses 15 serving functionally as finger grips for raising the locking 70 plates or latches. To retain the locking plates in the walls 4, 6, and 7 said locking plates are provided with vertical openings 16 and through these openings extend rivets or pins 17 carried by the plates 10, these 75 pins or rivets limiting the upward and downward movement of the locking plates within said walls.

80 The plates 2 and 3 have the vertical edges thereof provided with corner pieces 18, and these corner pieces limit the outward movement of the walls 4, 6, and 7, besides protecting the corners of the box.

85 19 denotes a lid having depending flanges 20 adapted to embrace the upper edges of the walls 4, 6, and 7. This lid is cut away, as at 21, to provide clearance for the upper reduced ends 14 of the plates 11 and the sides of the lid are provided with hinged off-set hasps 22 adapted to be engaged by 90 swiveled hooks 23 carried by the outer plates 10 at the side of a box. Staples can be substituted for these swiveled hooks in order that the lid can be locked upon the box.

95 To provide clearance for the swiveled hook carried by the wall 4 that is first folded inwardly, the inner plate 10 of the opposite wall 4 is cut away, as at 24.

100 In order that easy access can be had to the recesses 15 by the fingers, the upper edges of the inner plates 10 are cut away, as at 25.

105 To provide clearance for the swiveled hook 23 carried by the outer plate 10 of the uppermost wall 4, when the box is folded, the underneath side of the lid 19 is cut away, as at 26.

110 When the walls of the box are folded inwardly, as best shown in Fig. 4 of the drawings, the lid can be fitted upon the collapsed box and to retain the lid thereon, the outer

plates 13 at the sides of the box are provided with swiveled hooks 27 to engage the hasp 22. The depending flanges 20 of the lid will fully protect the walls when collapsed and prevent dirt and other matter from passing between the walls, particularly when being transported.

The box herein shown and described has been particularly designed as an egg crate 10 and collapsible pasteboard partitions employed for holding and separating eggs can be packed in the bottom of the box between the bottom plate 1 and the lowermost side wall 4. The box is made of wood with the 15 trimmings thereof of metal, and in lieu of solid walls slats or frames can be employed.

What I claim, is:

1. A collapsible box embodying a bottom plate, vertical plates carried by the edges of 20 said bottom plate, side walls hinged to said vertical plates and adapted to fold inwardly one upon the other, front and rear walls hinged to said vertical plates and adapted to fold inwardly one upon the other on top of 25 said side plates, locking plates slidably mounted in said walls, said plates being of a greater length than the depth of said walls to extend into the vertical plates of said bottom plate and hold said walls in a vertical

position, and a lid adapted to fit upon the 30 upper edges of said walls.

2. A collapsible box embodying a bottom plate, vertical plates carried by the edges of 35 said bottom plate, walls hinged to said vertical plates and adapted to fold inwardly one upon the other, locking plates slidably mounted in said walls and adapted to engage in the vertical plates of said bottom plate, a lid adapted to fit upon the upper edges of said walls, and means for connecting 40 said lid to said walls.

3. A collapsible box embodying a bottom plate, vertical plates carried thereby, walls hinged to said vertical plates and adapted to fold inwardly one upon the other, a lid adapted 45 to fit upon the upper edges of said walls, and means adapted to hold said walls in a vertical position, said means including outer and inner plates carried by said walls, and locking plates slidably mounted between said 50 inner and outer plates and adapted to enter said vertical walls.

In testimony whereof I affix my signature in the presence of two witnesses.

CHARLOTTE DICKIE.
